J. A. B. SMITH

TYPEWRITING MACHINE

Filed Aug. 21, 1925

UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed August 21, 1925. Serial No. 51,552.

This invention relates to stencil-card holding and typing devices for typewriting machines. Certain features of the device, embodying the present invention, are disclosed 5 in the co-pending application of Alfred G. F. Kurowski, Serial No. 43,492, filed July 14, 1925.

Extra long stencil-cards, used in some addressing machines, have information 10 typed on their back sides, below the usual small stencil-sheet. One of the features of the present invention is the provision of a card-holding frame arranged with stops above its bottom for use in stencil-card devices, with which information may be readily typed below the stencil-sheet on the back 15 of a stencil-card.

According to the present invention, the card-holding frame is arranged to be raised 20 and lowered on a track fast on end frames mounted on the carriage of a typewriting machine, upon manipulation of a handle fast to a geared sector at the right of the carriage. The sector is arranged to drive 25 up or down, through an intermediate pinion and gears mounted on the platen-shafts, racks fast on said frame. Means are provided whereby the ribbon-shifting mechanism is automatically silenced or made operative according as the card-holding frame 30 is raised or lowered.

The frame may have two upright side pieces arranged adjacent the ends of the platen of the typewriting machine, and a 35 flange on each side piece for supporting a card tangent to the platen. A strip on the bottom of the frame holds the lower edge of the card against the flange, and fingers hold the card against the flanges at the 40 top. Stops pivoted on each side piece and arranged for holding a card above the bottom may be swung out of engagement with the card when not in use.

A stencil-card is normally inserted face 45 forward in the frame with the stencil-sheet down. The card may then be typed on the front upper body-portion and stencils cut in the stencil-sheet without requiring the operative's attention to the shifting of the 50 ribbon. After removing the card, the stops may be set, and the card inserted with its back side to the operative and with the stencil-sheet up. With the frame in its lowest 55 position, characters may now be typed on the back of the card.

Other features and advantages will hereinafter appear.

In the accompanying drawings, Figure 1 is a fragmentary front elevational view of an Underwood typewriter having 60 the invention applied thereto.

Figure 2 is a fragmentary cross-sectional view of the same, the lower position of the card-holding frame being indicated by dot-and-dash outline. 65

Figure 3 is a partial front view of the card-holding frame of the invention, showing the stencil-card in place, arranged for having characters typed on its back side.

Figure 4 is a cross-section along the lines 70 4-4 of Figure 3.

This invention is illustrated as applied to an Underwood standard typewriting machine arranged for typing stencil-cards used 75 in addressing machines. A stencil-card 10 has a body 11 of heavy paper or cardboard, in which is provided a window or opening 12, over which is secured a thin, tightly-stretched stencil-sheet 13. Vertical columns 14 and 15 are provided on the front and 80 back, respectively, of the body 11, in which may be typed data for identification and other purposes. The data is preferably typed upon the back of the card below the opening 12, as illustrated in Figure 3. This 85 data may be conveniently typed on the card 10 in the device of the kind disclosed in the above noted application arranged with certain improvements of the present invention. 90

The card 10 may be inserted in the top of a card-holding frame 16, between two upright side frame-members 17 provided with rear flanges 18 arranged to extend a short distance behind the right and left sides of the 95 card to within a close proximity of the ends of a platen 19. A downwardly-extending flexible guide-finger 20 may be fastened to the top and on the front of each side frame-member 17. The upper ends of the fingers 100 may be flared outwardly, and the upper ends of the flanges 18 may have inwardly-extending portions 18^a to permit easier insertion of the cards. The lower ends of the fingers 20 may have a convex curve, whereby the 105 fingers may press downwardly on the top of the card 10 to hold it against the bottom of the frame 16. A spring strip 21 provided with tabs 22, may be fastened on the front 110 at the bottom of the frame 16, and arranged

to press against the bottom of the card for holding it in place.

When it is desired to cut stencils in the sheet 13, or type data on the front of the body 11, the card 10 may be pushed all the way down in the frame 16 with the stencil-sheet 13 below the main portion of the body, as illustrated in Figure 1. The operator will then pull forward a handle 25, which is fastened to a geared sector, not shown, which meshes with a pinion, not shown, mounted on a platen-shaft 26. Gears, not shown, are mounted on the platen-shaft, and mesh with racks 27 fast on the side frames 17, and the latter are caused to move downwardly along a track consisting of rearwardly-inclined flanges 28 fast on side plates 29 upon forward movement of the handle. The side plates are mounted on a typewriter-carriage 30. The top portion of the body 11 is thus brought tangent to the platen 19 at its printing point, which, as indicated by type 30^a, is below a horizontal plane through the center of the platen-shaft. As is fully disclosed in the above-noted application, when the frame 16 is lowered, a flange 31, fast on its lower edge, engages a tooth 32 of a plate 33, fast on a shaft 34, and, revolving the plate clockwise, moves upwardly a link 35, which causes a ribbon-vibrating mechanism, not shown, to be operatively connected with a universal bar 36, which is moved by engagement with the usual heel of type-bars, not shown. When the frame 16 is raised, the flange 31, engaging a tooth 37 and revolving the plate 33 counterclockwise, disengages the ribbon-vibrating mechanism of the machine, and silences a ribbon 38 in a ribbon-guide 38^a. Thus, if a key, not shown, be operated while the frame 16 is lowered, a character may be printed on the body 11. After a line of characters has been typed, the platen 19 may be line-spaced by a finger-piece 39 or a finger-wheel 39^a, and one or more additional lines typed. To cut stencils in the sheet 13, the handle 25 may be swung rearwardly, and the frame 16 will be raised the right amount to bring the top of the stencil-sheet to the printing line, and the ribbon 38 will also be silenced. To cut more than one line of stencils the platen 19 may be line-spaced by the usual means.

To type data in convenient reading position on the back of the card 10, the latter may be inserted in the frame 16 with the stencil-sheet opening 12 at the top of the body 11, as illustrated in Figure 3. Should the card 10 be then pushed all the way down in the frame 16, and the top of the data-columns 15 be brought to the printing line by operation of the handle 25, as explained above, the ribbon 38 will be automatically silenced, and characters cannot be typed. It is therefore desirable to provide means

for stopping the card above the bottom of the frame 16. To this end, I provide two stops 40, pivoted on the frame-members 17 about pins 41, arranged so that the top ends of the stops may engage and hold the lower edge of the card 10 approximately half-way between the top and bottom of the frame 16. Each stop 40 is provided with two notches 42 and 43 in its back or outer edge, which are arranged to engage with a V-shaped bend 44 in a detent-spring 45 mounted on the same flange 18 with the stop. When the card 10 is being stenciled or typed on the front side, the stops 40 may be held out of the way, as illustrated in Figure 1, with the springs 45 engaging with the upper notches 42. When data is to be typed on the back of the card, the stops may be easily set to catch under the lower edges of the card by pressing outwardly on the lower portions 46 of the stops below the pivot-pins 41, until the springs 45 engage in the lower notches 43. The frame 16 may then be brought to its lowest position, and the card 10 inserted. To hold the lower portion of the card 10 in the frame 16, when using the stops 40, a guide-finger 50 is mounted on each side plate 29 and extends inwardly to bear lightly against the body 11. The inner ends of the fingers 50 are turned upwardly, and are also bent outwardly.

By holding the card 10 in the frame 16 with the card-engaging fingers 20, and the strip 21 positioned at the extreme upper and lower ends, respectively, of the card, characters may be typed on the front of the card 10 at the extreme ends of the platen, and there will be no danger of the types striking these card-holding instrumentalities, as there would be were they positioned at the sides of the card intermediate the ends. The guide-fingers 50 are preferably positioned just enough above the printing line to clear the ribbon-guide 38^a. This arrangement permits the ribbon-guide to extend past the ends of the platen 19, and thus characters may be typed on the back of the card 10 at the extreme ends of the platen. It also guards against the type 30^a striking the fingers 50.

Variations may be resorted to within the scope of the invention, and portions of the improvements may be used without others.

Having thus described my invention, I claim:

1. In a typewriting machine having a platen, a ribbon, and a stencil-card device, in combination, a stencil-card-holding frame arranged for being raised and lowered in front of said platen, means for automatically silencing said ribbon when said frame is raised, and stops mounted on said frame and arranged for supporting a stencil-card in said frame above the bottom edge there-

cf, whereby characters may be typed on the back of said card below the stencil-sheet thereof.

2. In a typewriting machine having a platen, a ribbon, and a stencil-card device, in combination, a stencil-card-holding frame arranged for being raised and lowered in front of said platen, means for automatically silencing said ribbon, and a stop pivotally mounted on each side of said frame and arranged for supporting a stencil-card in said frame above the bottom thereof, said stops being arranged to be swung out of the way when not in use, so that cards may rest on the bottom of said frame.

3. In a typewriting machine having a platen, a ribbon, and a stencil-card device, in combination, a stencil-card-holding frame arranged for being raised and lowered in front of said platen, means for automatically silencing said ribbon when said frame is raised, a stop pivotally mounted on each side of said frame and arranged for supporting a stencil-card in said frame above the bottom thereof, and a detent spring mounted on each side of said frame under the adjacent stop, each of said stops being arranged with two notches in its lower end for engagement with a bent portion of the adjacent detent spring, whereby the stops may be latched in operative or inoperative positions.

4. In a typewriting machine having a platen and a ribbon, in combination, a stencil-card device, including an upright track and a frame engaging in and movable on said track and arranged for operatively holding tangent against said platen a flat stencil-card having a body-portion and a stencil-sheet normally below said body-portion, means arranged for automatically silencing said ribbon when said stencil-sheet, being normally disposed in said frame, is brought to the printing line of said platen, and means for supporting said stencil-card in said frame, so that characters may be typed on the back side of its body-portion when the latter is disposed below said stencil-sheet.

5. In a typewriting machine having a platen, a ribbon, and a stencil-card device, in combination, a frame arranged for being raised or lowered and for holding tangent against said platen a stencil-card having a body-portion and a stencil-sheet at the lower end thereof, and further arranged for silencing the ribbon of said machine when said stencil-sheet is brought in contact with said platen, and means on said frame arranged for supporting said stencil-card in position to have characters typed on the back side of its body below said stencil-sheet, said means being arranged to be held out of engagement with said card at will.

6. In a typewriting machine, in combination, a platen, a ribbon-vibrator, a stencil-card-holding frame arranged to be raised and lowered in front of said platen, means controlled by a handle for raising said frame a predetermined amount, means actuated upon raising said frame a predetermined amount for silencing said ribbon, and stops carried by said frame for supporting a card above the bottom of the frame.

7. A card-supporting stop for holding a card in a stencil-card frame above the bottom thereof, said stop including an upwardly-extending member pivoted through its lower end and having its upper end arranged to engage the card and its lower end portion being arranged with two notches, and a detent-spring arranged to engage in one of said notches for holding said member in effective position, and to engage in the other one of said notches for holding said member in ineffective position.

8. A frame for holding a card in a stencil-card device tangent to the platen of a typewriting machine, including two upright side-frame-pieces arranged at the right and left of said platen, a cross-piece joining the lower ends of said side pieces and forming a bottom support for said card, a flange arranged on each of said side pieces to extend a short distance behind said card, a strip fast on the front of said cross-piece arranged to engage against the front of said card at the bottom thereof, and a downwardly-extending flexible finger-strip mounted on the front of each of said side pieces adjacent the tops thereof, each of said finger-strips having its lower end formed with a concave curve arranged to engage against the top edge of said card for pressing the same downwardly against said cross-piece.

9. In a typewriting machine, in combination, a frame for supporting in typing position a card inserted downwardly in said frame, and a pair of stops for holding said card above the bottom of said frame, said stops including upwardly-extending members pivoted adjacent their lower ends to the sides of said frame, said members each having two notches in their lower portions adjacent their pivots, and detent-springs mounted on the sides of said frame and arranged for engaging in said notches, whereby said stop-members may be held in effective position for supporting a card above the bottom of the frame, or held in ineffective position at the sides of the card-receiving opening in said frame.

10. A frame for holding a card in a stencil-card device tangent to the platen of a typewriting machine, including two upright side pieces, a cross-piece joining the lower ends of said side pieces, flanges fast on said side pieces extending inwardly to engage behind the sides of the card, and a downwardly-extending flexible finger mounted at the

top of each side piece, each of said fingers having a concave lower end arranged to engage against the top edge of the card for pressing it downwardly against said cross-piece, said fingers also disposed over the flanges whereby they may serve as guides for cards being inserted in said frame.

11. In a typewriting machine, in combination, a carriage, two members of an upright track on said carriage, a platen disposed between said members, a frame movable on said track and having means arranged for supporting a card tangent to said platen, said means including two flanges 15 extending inwardly from the side pieces of said frame within close proximity of said platen, the front surfaces of said flanges being disposed in a plane tangent to said platen, a cross-piece between said flanges 20 against which the bottom of a card may rest, instrumentalities for holding the bottom side edges of said card against said flanges, and resilient fingers mounted at the top of said frame for holding the top side 25 edges of said card against said flanges and for pressing the bottom of the card against said cross-piece.

12. The combination with a typewriting machine having a carriage, a platen, a ribbon and a ribbon-silencing mechanism, of a side plate mounted on said carriage at each end of said platen, a track on said plates, a card-holding frame movable up and down on said track in front of said platen and engaging with said ribbon-silencing mechanism to cause said ribbon to be silenced when the frame is in its down position, two flanges on said frame extending within close proximity of the ends of said platen so that 30 a card held thereon will be tangent with said platen, and a finger mounted on each of said side plates and arranged to extend inwardly and press lightly on said card a short distance above the printing line.

13. The combination with a typewriting machine having a carriage, a platen, a ribbon and a ribbon-silencing mechanism, of a side plate mounted on said carriage at each end of said platen, a track on said plates, a 35 card-holding frame movable up and down on said track in front of said platen and engaging with said ribbon-silencing mech-

anism to cause said ribbon to be silenced when the frame is in its down position, two flanges on said frame extending within close 55 proximity of the ends of said platen and arranged so that a stencil-card held thereon will be tangent to said platen, a finger mounted on each of said side plates and arranged to extend inwardly and press lightly 60 on said card a short distance above the printing line, and a stop mounted at each side of said frame and arranged for engaging under the lower edges of said stencil-card to hold the same above the bottom of said 65 frame.

14. The combination with a typewriting machine having a carriage, a platen, a ribbon and a ribbon-silencing mechanism, of a side plate mounted on said carriage at each 70 end of said platen, a track on said plates, a card-holding frame movable up and down on said track in front of said platen and engaging with said ribbon-silencing mechanism to cause said ribbon to be silenced when the 75 frame is in its down position, two flanges on said frame extending inwardly a short distance and arranged so that a stencil-card held thereon will be tangent to said platen, and a stop mounted at each side of said 80 frame arranged for engaging under the lower edge of said stencil-card to hold the same above the bottom of said frame.

15. A frame for holding a card in a stencil-card device mounted on a typewriting 85 machine having a platen, including a side frame-piece positioned adjacent each end of said platen, a cross-piece joining the lower ends of said frame-pieces, a narrow inwardly-extending flange on each of said side 90 frames arranged so that said card held against the flanges will be tangent to said platen, each of said flanges having a small portion at its upper end extending inwardly beyond the narrow lower portion, and a 95 guide-finger mounted on each of said side pieces adjacent the top thereof and extending inwardly over said flanges, said fingers being flared outwardly at the top to form with said top portions of said flanges a convenient entrance for cards being inserted in 100 said frame.

JESSE A. B. SMITH.
